UNITED STATES PATENT OFFICE

ANTON HERTEL, OF HEIDELBERG, GERMANY

VENTILATOR

Application filed February 12, 1929, Serial No. 339,388, and in Germany February 21, 1928.

This invention relates to improvements in ventilators.

The objects of the invention are to provide a ventilator having means, such as flaps or valves, which automatically open under the influence of the escaping air from the inside of a room or car equipped with the improvement, the flaps being arranged to close when the incoming draft becomes stronger than the outgoing draft; said flaps being associated with adjustable means for controlling their opening movement.

The invention also relates to the specific means employed to adjust the opening movement of the flaps, whereby the position of the latter may be under control.

The invention also comprehends improvements in the details of construction and arrangement of parts which will be hereinafter described and particularly pointed out in the claims.

In the drawings:

Fig. 1 is a horizontal section of a chimney showing the application of the invention.

Fig. 2 is a front view of the ventilator.

Fig. 3 is a vertical section on the line 3—3 of Fig. 2.

a designates a portion of a chimney having an opening *b*. Inserted in the opening *b* is a cylindrical casing *c*, open at its inner end, and covered on its outer end with an ornamental rosette *d*, having a series of slots *d'*, the rosette being attached by screws to ears *c'* on the cylindrical casing *c*.

Mounted in the outer end of the cylindrical casing *c* adjacent the rosette are two flaps or valves *e*, pivoted at their upper and lower ends at *f*. These flaps are vertically disposed and are preferably made of thin sheet metal, and when in closed position close the end of the casing against the passage of draft.

It is desirable to limit the opening movement of the flaps in order to regulate the outgoing draft, and I therefore provide adjustable means to accomplish this function. This means consists of a slidable stop *g*, arranged in the bottom of the casing *c*, with means associated therewith for controlling its position.

Depending from the stop *g* is a lug *g'* which

passes through a slot *c'* in the bottom of the casing. The stop is arranged adjacent the lower ends of the flaps *f*, and is provided with a spring *h*, having one end attached to said stop and its opposite end attached to the casing, the tension of the spring being such as to draw the stop toward the rear end of the slot. A cord or chain is attached to the front end of the stop, and is guided over a pulley *k* to a convenient place in the room.

By adjusting the position of the stop, the opening movement of the flaps can readily be controlled and thereby regulate the draft passing from the room, or if desired closing the casing against the passage of air.

In operation, the position of the stop is regulated, and the air from the room will open the flaps, and such air will pass to the chimney. If the incoming draft is stronger than the outgoing draft, the flaps or valves will be automatically closed, as well understood in this art. If the flaps open too wide and thereby permit the passage of too much air from the room, the stop *g* is adjusted to the desired position by pulling on the cord or chain and securing the same, hence the opening movement of the flaps is limited. Of course, if the stop is drawn up to contact with the flaps, the draft will be entirely cut off, this at times being desirable.

The rosette presents an ornamental appearance to the ventilator, and the same time it does not detract from the operation of the flaps.

It is to be understood that the invention is not limited to the use of two flaps, as it is evident one or more may be used if desired.

What I claim is:

1. A ventilator comprising a casing open at one end, a rosette having openings and arranged over the outer end of the casing, pivotally mounted flaps in the outer end of the casing adjacent the rosette, a stop spring actuated in one direction, in the bottom portion of the casing near the lower ends of the flaps which cooperates with said flaps to regulate their open position, and means for adjusting the position of the stop to regulate the opening of the flaps.

2. A ventilator comprising a casing, piv-

totally mounted valve means in the casing, a stop mounted in the casing adapted to be positioned in the path of movement of the valve means, a spring to limit the movement of the stop in one direction, and manual means for moving the stop in the opposite direction, whereby to regulate the opening movement of the valve means.

In testimony whereof I affix my signature.
10 ANTON HERTEL.
